Patented June 11, 1912.

COLUMBIA PLANOGRAPH CO., WASHINGTON, D. C.

UNITED STATES PATENT OFFICE.

JOSEPH H. UNDERWOOD, OF ROSCOE, PENNSYLVANIA.

RAIL-JOINT.

1,029,407.

Specification of Letters Patent. Patented June 11, 1912.

Application filed March 1, 1912. Serial No. 680,950.

To all whom it may concern:

Be it known that I, JOSEPH H. UNDERWOOD, a citizen of the United States, residing at Roscoe, in the county of Washington 5 and State of Pennsylvania, have invented certain new and useful Improvements in Rail-Joints; and I do hereby declare the following to be a full, clear, and exact description of the invention, such as will enable others skilled in the art to which it appertains to make and use the same, reference being had to the accompanying drawings, and to letters and figures of reference marked thereon, which form a part of this 10 specification.

This invention relates to new and useful improvements in rail joint connections and comprises a simple and efficient means whereby strain at the joints may be reduced 15 to a minimum and in the provision of means for securely holding the ends of a rail without the use of bolts which are now commonly employed for this purpose and which, owing to vibration incident to trains passing 20 over the rails, tend to loosen the bolts, resulting in frequent accidents.

The invention comprises various details of construction and combinations and arrangements of parts which will be hereinafter 25 fully described and then specifically defined in the appended claim.

I illustrate my invention in the accompanying drawings, in which:

Figure 1 is a perspective view of a rail joint made in accordance with my invention. Fig. 2 is a cross sectional view taken on line 2—2 of Fig. 7. Fig. 3 is a cross sectional view on line 3—3 of Fig. 7. Fig. 4 is a detail perspective view of one of the 30 clamping plates. Fig. 5 is a detail view of another of the clamping plates. Fig. 6 is a view of a portion of a rail, and Fig. 7 is a horizontal sectional view through the two clamping plates interlocked without the rail.

Reference now being had to the details of the drawings by letter, A designates one of the clamping plates which is made preferably of the shape shown in Fig. 1 of the drawings and provided with a base portion A' designed to rest upon the ties of a railway, and the upright portion A² adapted to engage the web of a railway rail. The upper surface of the base A' is provided with transverse recesses B which extend 45 underneath the sides A² and in the bottom of each recess are formed holes D for the

reception of spikes. Intermediate the said recesses and projecting from the upper surface of the raised portion C are the lugs E, spaced apart.

F designates a rail of the usual construction, one of the flanges of which is recessed as at F' for the reception of one of said lugs E, as shown clearly in the sectional view of the drawings. It will be noted that said base A' has raised portions A³ near its ends and upon which adjacent ends of two rails, each interlocked with a lug E as shown and described, rest. A plate N, a detail view of which is shown in the drawings, is provided with an upright web engaging portion N' which is similar in construction to the upright portion A² upon the plate A. Wings O project laterally from the bottom of the plate and are adapted to slide in the recesses B formed in the upper surface of the bottom A' of the plate A and extend underneath the side A², it being noted that the recesses extend entirely through the lower portions of said side A², and each 50 wing O is provided with an aperture O' which, when the two plates are adjusted together in clamping relation with the rail, is in registration with an aperture D formed in the bottom of the recess outside the lower edge of the upright portion A². It will be noted that the flange N² formed near the lower edge of the wall N' is provided with apertures H which, when the plates are adjusted in clamping relation, are in registration with the apertures D' and are adapted to receive spikes I.

In adjusting my improved rail connection, the adjacent ends of two rails, each provided with a recess F' formed in one flange, are 55 placed upon the raised portions A³ and C of the plate A with the lugs E engaging the recesses F', in which positions the ends of the rail will contact with each other, after which the plate N is adjusted in place by 60 causing the lateral extensions O thereof to slide through the recesses underneath the flanges of the rails and, when the plates are in their proper clamping relation, the apertures in the wings O will be in registration 65 with the apertures D and the apertures H will be in registration with the apertures D' in the bottom of the plate A for the reception of the spikes which hold the plates in their adjusted positions.

By the provision of a rail joint made in accordance with my invention, it will be

5 noted that the usual fish plates which require bolts, which pass through registering apertures therein and through the web of the rails, are dispensed with and, by the provision of the clamping plates made in accordance with my invention, the two plates when interlocked will be held positively against independent longitudinal movement and with the spikes passing through the registering apertures the two plates will be securely locked from lateral movement away 10 from the flanges of the rail.

15 By the provision of a rail joint made in accordance with my invention, the wear at the joints of the rails will be reduced to a minimum and all danger incident to nuts upon bolts commonly used for fastening the fish plates will be avoided.

20 What I claim to be new is:—

25 A rail joint comprising two plates, one of which has an integral rail engaging flange and transverse recesses in the upper surface of the plate and which recesses communicate with openings in the lower portion of

30 the flange, the upper surface of the recessed plate having raised portions adjacent to the ends and underneath said flange, lugs integral with the flange and raised portion underneath the latter, the other of said plates having a flange and lateral projections parallel to each other and adapted to slide in said recesses and through the openings in the flange of the first referred to plate, said projections and bottom of the openings having registering apertures for 35 the reception of fastening means, the inner end of each of said projections upon the second referred to plate terminating in a shoulder adapted to contact with the raised portions at the ends of the recessed plate to 40 limit the movements of the two plates toward each other, as set forth.

In testimony whereof I hereunto affix my signature in the presence of two witnesses.

JOSEPH H. UNDERWOOD.
